INVENTOR

Adolph Hepner
BY
Emil Stanek
ATTORNEY

UNITED STATES PATENT OFFICE.

ADOLPH HEPNER, OF ST. LOUIS, MISSOURI.

COMBINED SHOE-HORN AND SHOE-REMOVER.

SPECIFICATION forming part of Letters Patent No. 732,854, dated July 7, 1903.

Application filed October 29, 1902. Serial No. 129,316. (No model.)

To all whom it may concern:

Be it known that I, ADOLPH HEPNER, a citizen of the United States, residing at St. Louis, State of Missouri, have invented certain new and useful Improvements in a Combined Shoe-Horn and Shoe-Remover, of which the following is a full, clear, and exact description, reference being had to the accompanying drawings, forming a part hereof.

10 My invention has relation to improvements in combined shoe-horns and shoe-removers; and it consists in the novel construction of parts more fully set forth in the specification and pointed out in the claims.

15 In the drawings, Figure 1 is a side elevation of my device, showing a person applying the same. Fig. 2 is a rear elevation thereof, showing its application in the act of removing an overshoe. Fig. 3 is a middle vertical section on line 3 3 of Fig. 4. Fig. 4 is a front elevation thereof corresponding to the position shown in Fig. 1—that is, for slipping on the shoe. Fig. 5 is a side view of Fig. 2, a portion of the counter or heel portion of the upper being removed; and Fig. 6 is a cross-section on line 6 6 of Fig. 4.

20 The object of my invention is to construct a device which shall not only facilitate the putting on of overshoes, but shall serve the purpose of removing the same, as will more fully hereinafter appear.

25 In detail the invention may be described as follows:

Referring to the drawings, 1 represents the body portion of the horn, the same being outwardly convex and terminating in a lower extension 2 of the form of a semicylinder and an upper stem 3. The base of the concavity constituting the portion 2 is substantially parallel to the axis of the stem 3 and to the handle-bar 4, carried by it, as best seen in Figs. 1 and 3, the parallelism being for a purpose presently to appear. The lower edge of the portion 2 is provided with a central tooth or projection 5, bounded on either side by a lobe 6, and the body portion 1 is a well-defined depression or pocket 7 for the initial

reception of the heel of the person putting on the rubber or overshoe. The sides or lateral edges of the device are substantially parallel, as best seen in Fig. 4, so that when inserted into the overshoe the counter-walls thereof may be well spread apart to facilitate the insertion of the heel of the shoe, Fig. 1.

50 In operating the device the person putting on the overshoe first inserts the lower end of the horn into the overshoe, with the horn against the counter or heel portion thereof, forcing the tooth 5 and lobes 6 against the bottom of the overshoe S, direct pressure thereupon being assured by reason of the parallelism of the portion 2 and the handle-bar 4, whereupon the overshoe S is given a slight tilt or inclination and the toe of the wearer 55 is initially inserted into the overshoe, the heel resting in the depression 7, when, as seen in Fig. 1, the slipping on of the shoe S is a matter of only a fraction of a second. To remove the overshoe, the device is brought against 60 the upper edge of the counter or heel thereof, the tooth 5 being inserted along the inner wall of said counter, whereupon the lobes 6 on either side span the outer wall of the counter, Figs. 2, 5, thus holding down the overshoe with sufficient firmness to permit the 65 wearer to withdraw his foot out of the shoe.

70 The present device is not to be confounded with the ordinary shoe-horn, for while it may possess some of the inherent purposes of such 75 horn it possesses functions and advantages different from those of an ordinary horn.

Having described my invention, what I claim is—

1. As an article of manufacture, a combined 85 shoe-horn and shoe-remover comprising an outwardly-convex body portion, a lower substantially semicylindrical extension, a central tooth and bounding lobes disposed along the lower edge of said extension, a pocket 90 forming a continuation of the curved wall of the body portion, a stem at the upper end of the body portion axially parallel with the longitudinal elements of the wall of the lower

extension, the lateral edges of the horn being substantially parallel for the major portion of their length, substantially as set forth.

2. In a shoe-remover, a curved body portion, a central tooth along the lower edge thereof for insertion along the inner surface of the upper edge of the overshoe, and lobes disposed on either side of the tooth for em-

bracing the outer wall of the counter of the shoe, substantially as set forth.

In testimony whereof I affix my signature in presence of two witnesses.

ADOLPH HEPNER.
